UNITED STATES PATENT OFFICE.

A STEVEN SCHULZ, OF BUDAPEST, HUNGARY, ASSIGNOR OF ONE-HALF TO FERDINAND HORVATH, JR., OF BUDAPEST, HUNGARY.

PROCESS OF PRODUCING VARIOUSLY-COLORED DECORATIVE DISKS OR SLABS.

1,307,886.

Specification of Letters Patent. Patented June 24, 1919.

Application filed July 20, 1914. Serial No. 851,977.

To all whom it may concern:

Be it known that I, A STEVEN SCHULZ, subject of the King of Hungary, residing at Budapest, Hungary, have invented certain new and useful Improvements in Processes of Producing Variously-Colored Decorative Disks or Slabs, of which the following is a specification.

This invention relates to a new process of producing variously sized and colored decorative disks or slabs showing a design which passes through their entire thickness, and which may be used either by themselves as buttons, nail-heads, etc., or inlaid or worked into tiles or plates such as are used in floor-coverings, wall-coverings, mosaics and the like. The invention consists in the novel way of working plastic materials such as are used in the manufacture of artificial stones.

The object of the invention is to produce from differently colored plastic materials used in artificial stone-making, decorative disks, slabs, tiles and plates which may be used for various purposes as for example covering floors, walls, inlaid furniture and the like, in a new, simple, easy, and cheap way, where no stencils, forms, molds or such like are used, and by which beautiful and effective designs or patterns can be produced.

The new process is carried out as follows:

Differently colored plastic materials such as are used in the manufacture of artificial stone are taken. From masses of this differently colored plastic material thin sheets and also suitably sized sticks are formed. Two or more of different color may then be rolled in and around one another as shown in Figure 1. According to another arrangement one or more sheets (of different colors when a plurality are used) are rolled around one or more colored sticks as shown in Figs. 2 and 3.

The cylindrical bodies so obtained are cut, either alone or combined with one another, into disks or slabs.

Further, several cylindrical bodies produced by rolling differently colored sheets into one another or around a plastic stick may be arranged side by side around a central core consisting of one or several plastic sticks (which may, if desired, have been previously wrapped around with, or rolled

into, one or more sheets) in such a way that the central core is surrounded on its whole circumference by such cylindrical bodies as shown in Fig. 4. The bundle obtained in this way is rolled with gentle pressure until the cylindrical bodies which form the bundle combine into another larger cylindrical body as shown in Fig. 5. Such body when cut perpendicularly to its axis thereby forming disks shows on the surface of the cut a flower like or rosaceous design. If this larger cylindrical body, obtained by the above described operations, is again wrapped around with, or rolled into, one or several plastic differently colored sheets and then cut into disks, the flower-like design appears on the surface of the disks surrounded by one or several differently colored rings.

In addition to those described other designs can, of course, be produced as, for example, the design of a rose as shown in Fig. 6. Here two differently colored sheets of plastic material are first rolled into one another. Around the stick obtained in this way several sticks (which have been previously rolled into a sheet and afterward pressed substantially flat or curved) are arranged so that they partly cover one another. The body so obtained after having been wrapped around with, or rolled into, one or several sheets, is cut, perpendicularly to its axis, into disks or slabs which on the surface show the design of a rose.

Of course several of the bundles produced in the above described way may be combined and united in various ways and by cutting these united bundles into a number of disks or slabs and placing the same in a large slab of plastic material we can obtain slabs with carpetlike design as shown for example in Fig. 7.

Having thus described this invention what is claimed and desired to secure by Letters Patent is:

1. A process of producing decorative slabs of plastic materials, which consists in rolling together several colored plastic masses to produce differently colored plastic sticks and arranging the sticks so formed side by side around a central core made of a plastic stick until the central core is surrounded by said sticks on its whole circumference, then rolling, with a gentle pressure, the bundle so obtained until the whole is united into a

substantially cylindrical body, and finally cutting said cylindrical body perpendicularly to its axis, into slabs.

2. A process of producing decorative slabs 5 of plastic materials, which consists in arranging a plurality of plastic sticks comprising a plurality of different colors, wrapped with a plastic sheet of a different color from said sticks, side by side around a plastic central core until this core is surrounded by said sticks, rolling the bundle so obtained with gentle pressure until the several sticks are united into a cylindrical body, wrapping said cylindrical body with a colored sheet of 10 plastic material, and finally cutting the body so obtained perpendicularly to its axis, into slabs.

3. A process of producing decorative slabs 20 of plastic materials, which consists in assembling differently colored pieces with one another to produce a stick, then arranging around the stick so obtained, and serving as a core, a plurality of plastic sticks which have each been previously wrapped with a 25 plastic sheet, such sticks being placed around the core in such a way that each of said plurality of sticks covers a portion of the said core, then gently pressing the bundle so obtained, and finally cutting the body so obtained perpendicularly to its axis, into slabs.

4. A process of producing decorative slabs

of plastic materials, which consists in producing plastic sticks by rolling different colored plastic pieces into and around one another, then taking the sticks so produced and arranging them side by side around a central plastic core until this core is entirely surrounded by said sticks, rolling the bundle so obtained into a multicolored body, then uniting several of the bodies so obtained into a 40 larger bundle, and finally cutting this larger bundle perpendicularly to its axis, into disks.

5. A process of producing decorative slabs 45 of plastic materials, which consists in producing plastic sticks each wrapped previously with a different colored sheet, placing these sticks side by side around a plastic core until this core is surrounded by such sticks, wrapping the bundle so obtained with a plastic sheet and then rolling the product 50 until it becomes cylindrical, cutting this cylindrical body into slabs, and finally placing a plurality of the slabs so obtained into soft plastic material, thereby producing plates having desired designs.

In testimony whereof I affix my signature in presence of two witnesses.

A STEVEN SCHULZ
